(57) **CLAIM**

The ornamental design for an endoscope sheath with oblique tip, as shown and described.

DESCRIPTION

FIG. 1 is a perspective view of an endoscope sheath with oblique tip showing our new design;

FIG. 2 is an enlarged, detailed view of the distal tip shown in the encircled portion in FIG. 1;

FIG. 3 is a first end-elevation view thereof;

FIG. 4 is a second end-elevation view thereof;

FIG. 5 is a first side-elevation view thereof;

FIG. 6 is a second side-elevation view thereof;

FIG. 7 is a top, plan view thereof; and,

FIG. 8 is a bottom, plan view thereof.

The dash-dash broken lines in the drawings illustrate portions of the endoscope sheath with oblique tip that form no part of the claimed design.

The endoscope sheath with oblique tip is shown with a symbolic break in its length. The appearance of any portion of the article between the break lines forms no part of the claimed design.
